ELECTRIC CORD PLUG

Andrew J. Gombar, Stratford, Conn., assignor to The Whitney Blake Company, Hamden, Conn., a corporation of Connecticut

Application June 8, 1955, Serial No. 36,426

Term of patent 14 years

(Cl. D26—1)

Fig. 1

Fig. 2

Fig. 3

Fig. 4

Fig. 5

Fig. 1 is a perspective view of an electric cord plug, showing my new design;

Fig. 2 is a perspective view of the device of Fig. 1, showing the same inverted and moved to a position end-for-end of that shown in Fig. 1;

Fig. 3 is a plan view of the same;

Fig. 4 is a side elevation of the same, looking from the bottom of Fig. 3; and

Fig. 5 is an end view of the same looking from the left in Fig. 4.

The dominant features of my design reside in the portions shown in full lines.

I claim:

The ornamental design for an electric cord plug substantially as shown and described.
